UNITED STATES PATENT OFFICE.

HUGO BAUM, OF NEW YORK, N. Y.

DESIGN FOR A DOLL.

Application filed March 28, 1924. Serial No. 9,090. Term of patent 3½ years.

To all whom it may concern:

Be it known that I, HUGO BAUM, residing at 45 Greene Street, in the city of New York, county of New York, and State of New York, have invented a new, original, and ornamental Design for Dolls, of which the following is a specification, reference being had to the accompanying drawing, forming part thereof.

In the drawing—

I claim:

The ornamental design for a doll substantially as shown.

HUGO BAUM.
